RECLINING ARTICLE OF FURNITURE

Anton Lorenz, Buffalo, N. Y.

Application February 15, 1946, Serial No. 647,690

16 Claims. (Cl. 155—106)

1

The present invention relates to articles of furniture and more particularly to a reclining article of furniture, wherein the seat and the back-rest are swingably mounted on a support. This application is a continuation-in-part of Patent No. 2,433,521, granted Dec. 30, 1947.

An object of the present invention is to provide an article of furniture of above described type with a mechanism, simple in construction for controlling the movements of the seat and back-rest in dependence on each other.

Another object of the present invention is to improve on the construction of articles of furniture of above described type as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of a reclining chair according to the invention, a portion of the side wall of the support being broken away,

Fig. 2 is an elevational view of the locking device of the chair shown in Fig. 1,

Fig. 3 is a sectional view of the locking device taken on line 3—3 of Fig. 2,

Fig. 4 is an elevational view of a detail of the locking device shown in Figs. 2 and 3,

Fig. 5 is a side elevational view of a different embodiment of a reclining chair according to the invention, a portion of the side wall of the support being broken away,

Fig. 6 is a sectional view taken on line 6—6 of Fig. 5,

Fig. 7 is a sectional view taken on line 7—7 of Fig. 6,

Fig. 8 is a perspective view of the support of the chair shown in Fig. 5, the controlling unit of the chair being mounted in said support,

Fig. 9 is an elevational view illustrating a safety device for holding the controlling unit of the chair shown in Figs. 5 and 8 in its place,

Fig. 10 is a perspective view of a different embodiment of a controlling unit, which may be used in the chair shown in Fig. 5,

Fig. 11 is a side elevational view of a further embodiment of a reclining chair according to the invention, a portion of the side wall of the support being broken away,

Fig. 12 is a side elevational view of another embodiment of a reclining chair according to the invention, a portion of the side wall of the support being broken away,

Fig. 13 is a fragmentary view of a detail of the

2

chair shown in Fig. 12 taken on line 13—13 of Fig. 12,

Fig. 14 is a side elevational view of a different embodiment of a reclining chair according to the invention, a portion of the side wall of the support being broken away,

Fig. 15 is a side elevational view of another embodiment of a reclining chair according to the invention, a portion of the side wall of the support of the chair being broken away,

Fig. 16 is an elevational view of a different embodiment of a controlling member, which may be used in the chair shown in Fig. 15,

Fig. 17 is an elevational view of a further embodiment of a controlling member, which may be substituted for the controlling member of the chair shown in Fig. 15,

Fig. 18 illustrates a different embodiment of a reclining chair according to the invention,

Fig. 19 illustrates a different embodiment of a controlling member which may be substituted for the controlling member of the chair shown in Fig. 18,

Fig. 20 is an elevational view of another embodiment of a controlling member which may be used instead of the controlling member of the chair shown in Fig. 1,

Fig. 21 is an elevational view of a further embodiment of a controlling member, which may be substituted for the controlling member of the chair shown in Fig. 1, and

Fig. 22 is an elevational view of another embodiment of a controlling member, which may be used in the chair shown in Fig. 1.

Referring now to Fig. 1, 30 indicates a casing-like support, wherein a back-rest 31 and a seat 32 are coaxially pivoted to the support at 33. The back-rest 31 has an extension 34 projecting downwardly beyond the pivotal connection 33 between the back-rest 31 and the support 30. On each side of the chair the rear end of a connecting link 35 is pivoted to said downward extension 34 of the back-rest 31 at 36. The front end of each connecting link 35 is pivoted at 37 to the lower end of a controlling link 38, the upper end of which is rigidly connected with a transverse rod 39 rotatably mounted in a suitable manner in the support 30. A controlling element or controlling arm 40 is positively connected with the upper end of each controlling link 38, so that it participates in the movements of such a controlling link. According to the embodiment shown in Fig. 1 the controlling arm 40 is integral with the controlling link 38 but, of course, the

controlling arm 40 and the controlling link 38 could be made of two separate members rigidly connected with each other in any suitable manner. The combination of each controlling link 38 connected with a controlling arm 40 represents a controlling member generally indicated by 21.

The transverse rod 38 and the two controlling members 21 rigidly connected with each other form a controlling unit generally indicated by 41. Each controlling arm 40 of said controlling unit 41 carries a rotatable roller for loose and displaceable engagement with the seat 32. The circumferential surface of said roller 42 and the lower surface of said seat 32 constitute cooperating controlling or abutting surfaces displaceably engaged with each other.

When the user of the chair leans the weight of his body against the back-rest 31, the latter will be swung about its pivot 33 into a reclined position, for example the extreme reclined position 31'. During such a swinging movement of the back-rest 31, the controlling unit 41 is swung into the position 41' through the medium of the connecting links 35 connected with said controlling unit 41 and the extension 34 of the back-rest 31. When the controlling unit 41 is swung into said position 41', the rollers 42 roll along the lower surface of the seat 32 which, in turn, is lifted into the reclined position 32'. On the other hand, when the back-rest and the seat are in the reclined position 31' and 32' respectively, and the user of the chair leans the weight of his body forwardly so as to exert a pressure on the front portion of the seat, the latter will be returned into the position shown in full lines, and during said return of the seat into the sitting position, the back-rest will be returned into the position shown in full lines through the medium of the controlling unit 41 and the connecting links 35. Thus, the mechanism 34, 35, 41 causes a movement of the seat 32 and the back-rest 31 in dependence on each other.

The movable members of the chair may be held in any desired position, for example above described extreme reclined position or any other intermediate reclined position, by means of a locking device generally indicated by 43. As best shown in Figs. 2 and 3, said locking device 43 comprises a member 44 swingably mounted at 45 on a lug 46 secured to the seat 32. The member 44 is provided with a longitudinal slot 47 engaged with a bolt 48 having a square portion 49 engaged with a corresponding square aperture of an element 50. Said element has a lug 51 on each side for abutting engagement with the member 44, which is in sliding engagement with said element 50. The head 52 of the bolt 48 rests against a surface of the element 50. The bolt 48 passes through the bore 53 of a disk 54, through a bore 55 of a side wall of the support 30, and through a bore 56 of a member 57 attached to the side wall of the support 30. A locking knob 58 is screwed on the threaded end of said bolt 48. The square portion 49 of the bolt 48 prevents the latter from rotation when the locking knob 58 is turned. As best shown in Fig. 4, the surface of the disk 54 is knurled, so as to increase the friction between said disk 54 and the member 44, when the locking knob 58 is tightened for pressing the various members and elements of the locking device against each other so as to hold the seat 32 and the remaining movable members of the chair in a predetermined position. When the locking knob 58 is loosened, the member 44 may freely slide along the bolt 48, so that the movable members of the chair may be readily moved from one position into another one. Of course, if desired, any other suitable locking device may be used in the chair shown in Fig. 1.

The sitting position of the movable members

of the chair shown in full lines is limited by the upper edge of the support 30, on which the seat 32 comes to a rest. The extreme reclined position 31', 41', 32' of the movable members of the chair shown in dash and dot lines is limited by an abutment of the edge 59 of the slot 47 of the member 44 against the bolt 48 of the locking device 43.

As mentioned above, the controlling rollers 42 of the controlling unit 41 are in loose engagement with the seat 32. In order to prevent a collapsing of the mechanism including the back-rest 31, the extension 34, the connecting links 35, and the controlling unit 41 in a forward direction when the seat 32 is in its sitting position, a stop 60 is arranged on the support 30 for abutting engagement with the extension 34 of the back-rest 31, when the seat 32 is in said sitting position. Of course, said stop 60 could be arranged at another place of the support for cooperation with another member of the mechanism 34, 35, 41, and furthermore said stop could be arranged at a member of said mechanism 34, 35, 41 for cooperation with another member of said mechanism.

Fig. 20 illustrates a different embodiment of a controlling member 21a, which could be used in the chair shown in Fig. 1 instead of the controlling member 21 formed by the controlling link 38 and controlling arm 40 rigidly connected with each other. According to Fig. 20 the controlling member 21a is in the shape of a plate having a bore 37a for a pivotal connection with a connecting link, having a bore 39a for engagement with the transverse rod, and having a bore 42a for receiving the shaft carrying the roller.

Fig. 21 illustrates another embodiment of a controlling member 21b, which could be used in the chair shown in Fig. 1 in a similar manner instead of the controlling member 21 formed by the controlling link 38 and controlling arm 40 rigidly connected with each other. The controlling member 21b shown in Fig. 21 may be obtained, for example, by cutting a V-shaped recess into a plate of the shape shown in Fig. 20. The left-hand edge of such a plate is indicated by dash lines in Fig. 21.

Fig. 22 illustrates still another embodiment of a controlling member 21c, which could be used in a similar manner in the chair shown in Fig. 1 instead of the controlling member 21 formed by the controlling link 38 and the controlling arm 40.

According to the embodiment of a reclining chair shown in Fig. 5, the back-rest 131 and the seat 132 are coaxially pivoted to the support 130 at 133. On each side of the chair one end of a connecting link 135 is pivoted to the downward extension 134 of the back-rest 131 at 136, and the other end of said connecting link 135 is pivoted to a controlling link 138 at 137. As best shown in Figs. 5 and 8 the upper end of each controlling link 138 is rigidly connected with a transverse rod 139 rotatably arranged in recesses 161 of the side walls of the support 130. Furthermore, one end of a controlling arm 140 is rigidly connected with said transverse rod 139 substantially in the center of the chair. The controlling arm 140 carries a roller 142 for loose engagement with the seat 132. The two controlling links 138, the controlling arm 140 and the transverse rod 139 form a controlling unit 141, which may be readily inserted into the slots 161 of the support 130 from above. Safety members 75 162 attached to the side walls of the support 130

by screws serve to hold said controlling unit 141 in its place (see Figs. 8 and 9). Collars 163 mounted on the transverse rod 139 prevent an axial displacement of the controlling unit 141.

A leg-rest 164 is swingably mounted on the front portion of the seat 132 at 165. One end of a controlling bar 166 is pivoted to said leg-rest 164 at 167, the other end of said controlling bar 166 is pivoted to an extension 168 of the controlling link 138 at 169. The controlling bars 166 and the extension 168 of the controlling link 138 may pass through a slot 170 in the front wall of the support 130.

When the back-rest 131 is swung from the position shown in full lines into the reclined position 131' about its pivot 133, the controlling unit 141 lifts the seat 132 into the reclined position 132' in the same manner as the controlling unit 41 of the chair shown in Fig. 1. Furthermore, the leg-rest 164 of the chair shown in Fig. 5 is swung into the position 164' by means of the controlling unit 141 connected with the leg-rest 164 through the controlling bar 166.

The movable members of the chair may be held in any desired position by means of a locking device generally indicated by 171. As best shown in Figs. 5-7 said locking device 171 includes a clamping sleeve 172 slidably engaged with a rod 173 attached to an arm-rest 174 swingably mounted on the back-rest 131 at 175. The threaded end 176 of the rod 173 passing through a bore of a block 177 secured to the arm-rest 174 is threaded into a threaded bore of another block 178 secured to the arm-rest 174. A bolt 179 having a head 185 resting against a surface of a member 181 rigidly and immovably connected at 182 (for example by welding) with a side wall of the support 130 and having a square portion 183 engaged with a corresponding square aperture of said member 181 is engaged with bores 183 of the clamping sleeve 172, so that the latter may swing about said bolt 179 when a locking knob 184 screwed on the threaded end of the bolt 179 is loosened. Thus, when said locking knob is loosened, the clamping sleeve 172 and the rod 173 form cooperating sliding means for guiding the arm-rest 174, so that the latter is brought into the position 174', for example, when the back-rest is brought into the position 131'. When, however, the locking knob 184 is tightened on the bolt 179 prevented from rotation by its square portion 183, clamping sleeve 172 is tightly pressed on the rod 173, so that the arm-rest 174 and the remaining movable members of the chair are held in a predetermined position.

The sitting position of the movable members of the chair is limited by the upper edge of the support 130 on which the seat 132 comes to a rest, and the extreme reclined position of the movable members of the chair is limited by an abutment of the clamping sleeve 172 against the surface 186 of the block 178 secured to the arm-rest 174.

Fig. 10 illustrates a different embodiment of a controlling unit 141d, which may be substituted for the controlling unit 141 of the chair shown in Figs. 5 and 8. According to Fig. 10 the controlling unit 141d is made of an integral piece of material and has only one controlling link 138d and one controlling arm 140d. Of course, if such a controlling unit 141d is used, the back-rest 131 of the chair shown in Fig. 5 has its downward extension 134 substantially in the center of the chair, and the chair has only a single connecting link 135 pivoted to said

extension of the back-rest and to the controlling link 138d of the controlling unit 141d.

According to the embodiment of a reclining chair shown in Fig. 11 the back-rest 231 and the seat 232 are coaxially pivoted to the support 230 at 233. The back-rest 231 has a downward extension 234 substantially in the center of the chair. Said extension 234 is connected with a controlling link 238 by means of a connecting link 235 pivoted to the extension 234 at 236 and pivoted to the controlling link 238 at 237. The upper portion of the controlling link 238 is swingably mounted on the support 230 at 239. One end of a telescopic controlling arm 240 is rigidly connected with an intermediate point of the controlling link 238, and the other end of said telescopic controlling arm 240 carries a roller 242 for loose and displaceable contact with the seat 232. The leg-rest 264 swingably mounted on the seat 232 at 265 is controlled by a telescopic controlling bar 266 pivoted to the leg-rest at 267 and pivoted to the bent extension 234 of the back-rest 231 at 267. The controlling bar 266 may pass through a slot 270 in the front wall of the support 230.

The sitting position of the movable members of the chair shown in full lines is limited by the upper edge of the support 230 carrying the seat 232. When the back-rest 231 is swung into the extreme reclined position 231' shown in dash and dot lines, the seat and the leg-rest are brought into the positions 232' and 264' by means of above described controlling mechanism.

The movable members of the chair may be held in any desired position by means of the locking device 243 of the type shown in Figs. 2 and 3.

The extreme reclined position 231', 232', 264, of the movable members of the chair is limited by the edge 259 of the slot 267 of the locking device 243 as described above in connection with Figs. 2 and 3.

Fig. 11 illustrates means for varying the effective length of the controlling arm 240. As mentioned above, the controlling arm 240 is of a telescopic construction, and after a loosening of the set screw 288, the element 289 of the telescopic controlling arm 240 may be displaced relative to the hollow element 290 thereof, whereupon the element 289 may be held in its adjusted position by tightening the set screw 288. Such an adjustment of the effective length of the telescopic controlling arm 240 causes a variation in the distances between the point of contact of the roller 242 with the seat 232 and the pivotal and swingable connections 237, 239 of the controlling link 238, whereby the angle between the seat 232 and the back-rest 231 may be altered.

In a similar manner, the angle between the leg-rest 264 and the seat 232 may be altered by an adjustment of the displaceable member 291 of the telescopic controlling bar 266 relative to the hollow member 292 thereof. Said adjustment of the telescopic controlling bar 266 results in an adjustment of the effective length thereof.

Furthermore, the extension 234 of the back-rest 231, the controlling link 238, and the controlling bar 266 are provided with a series of holes 293 for selective engagement of the pins 236, 237, and 267 so as to change the relationship of the various members of the link mechanisms relative to each other for adjustments of the angles between the back-rest 231, the seat 232, and the leg-rest 264.

According to the embodiment of a reclining chair shown in Fig. 12 the back-rest 331 is pivoted

7
to the support 330 at 333. The rear end of the seat 332, however, is pivoted to the support 330 at 394 at a point spaced from the pivotal connection 333 between the back-rest 331 and the support 330. Furthermore, the controlling arm 340 carrying the roller 342 for loose engagement with the seat 332 is rigidly connected with the lower end of the controlling link 338 adjacent the pivotal connection 337 of the latter with the connecting link 335 pivoted to the extension 334 of the back-rest 331 at 336. The upper end of the controlling link 338 is swingably mounted on the support 330 at 399.

The leg-rest 364 swingably mounted on the seat 332 at 365 is pivoted at 367 to one end of a controlling bar 366. The other end of said controlling bar 366 is pivoted at 395 to one end of an adjusting element or bar 396 (see Figs. 12 and 13), the other end of which is swingably mounted on the controlling link 338 at 397. A stop 398 secured to the controlling link 338 by screws is arranged for engagement with the swingable adjusting bar 396, so as to hold same in alignment with the controlling link 338 as shown in full lines in Fig. 12.

When the back-rest 331 is swung about its pivot 333 into the extreme reclined position 331' shown in dash and dot lines, above described mechanisms cause a movement of the other movable members of the chair into the positions likewise shown in dash and dot lines, i. e. the seat and the leg-rest are brought into the positions 332' and 364'.

The movable members of the chair may be held in any desired position by means of the locking device 343 of the type shown in Figs. 2 and 3, which also limits the extreme reclined position of the movable members of the chair.

As mentioned above, the adjusting bar 396 is swingable about the pivot 397. If the back-rest and seat are held in a predetermined position, for example the sitting position shown in full lines in Fig. 12 by means of the locking device 343, the leg-rest 364 may be swung by hand about its pivot 365 into the position 364'', wherein the controlling bar and the adjusting bar are in the positions 366'' and 396'' in alignment with each other. Now, when a slight pressure is exerted on the leg-rest, for example by the legs of the occupant resting in the chair, the controlling bar and the adjusting bar are moved slightly beyond said straight line, until a stop 399 secured to the adjusting bar 396 by screws abuts against the controlling bar, whereby said elements are locked and held in a predetermined position relative to each other.

According to the embodiment of a reclining chair shown in Fig. 14, the back-rest 431 and seat 432 are coaxially pivoted to the support 430 at 433. The lower end of each controlling link 438 is pivoted at 437 to one end of a connecting link 435, the other end of which is pivoted to the downward extension 434 of the back-rest 431 at 436. One end of a controlling arm 440 is rigidly connected with the upper end of each controlling link 438 adjacent the swingable mounting 439 thereof. The other end of each controlling arm 440 is pivoted at 460 to one end of a controlling rod 461, the other end of which is pivoted to the seat 432 at 462.

The leg-rest 464 swingably mounted on the seat 432 at 465 is pivoted at 467 to one end of a controlling bar 466, the other end of which is pivoted at 487 to the bent extension 434 of the back-rest 431.

5 When the back-rest 431 is swung from the full-line position into the reclined position 431', the controlling link 438 integral with the controlling arm 440 is brought into the position 438', 440', so that the seat 432 is lifted into the position 432' through the medium of the controlling rod 461 pivotally connected with the controlling arm 440 and the seat 432. Furthermore, the leg-rest 464 is brought into the position 464' through the medium of the controlling bar 466 pivotally connected with the leg-rest 464 and the extension 434 of the back-rest 431.

10 The sitting position of the movable members of the chair is limited by an abutment of the seat 432 against the upper edge of the support 430. The movable members of the chair may be held in any desired position by means of the locking device 443 of the type shown in Figs. 2 and 3, which also limits the extreme reclined position of the movable members of the chair.

15 According to the embodiment of a reclining chair shown in Fig. 15, the back-rest 531 and the seat 532 are coaxially pivoted to the support 530 at 533. The downward extension 534 of the back-rest 531 is pivoted at 536 to one end of a connecting link 535, the other end of which is pivoted at 537 to the upper portion of a controlling link 538. The lower portion of said controlling link 538 is swingably mounted on the support 530 at 539. One end of a controlling arm 540 is rigidly connected with the lower end of said controlling link 538 adjacent the swingable mounting thereof. According to Fig. 15, the controlling arm 540 is integral with the controlling link 538 but, of course, the controlling arm and the controlling link could be made of two separate members rigidly connected with each other in any suitable manner. One end of a controlling rod 501 is pivoted at 500 to the controlling arm 540 of the controlling member generally indicated by 521, the other end of said controlling rod is pivoted at 502 to the seat 532.

20 When the back-rest 531 is swung from the full-line position about its pivot 533 into the extreme reclined position 531', the seat 532 is lifted from the full line position into the reclined position 532' by means of the controlling mechanism 534, 535, 538, 540, 501.

25 The sitting position of the movable members of the chair is limited by an abutment of the seat 532 against the upper edge of the support 530. The extreme reclined position of the movable members of the chair is limited by the abutment of the controlling arm 540 against a stop 503 arranged on the support 530. Said stop 503 prevents a movement of the controlling arm 540 and the controlling rod 501 into or beyond a straight line, which might result in a locking of the movable members of the chair.

30 The movable members of the chair may be held in any desired position by means of the locking device 543.

35 Fig. 16 illustrates a different embodiment of a controlling member 521e, which could be used in the chair shown in Fig. 15 instead of the controlling member 521 formed by the controlling link 538 and controlling arm 540 rigidly connected with each other. According to Fig. 16 the controlling member 521e is in the shape of a plate having a bore 537e for a pivotal connection with the connecting link, having a bore 539e for engagement with the transverse rod and having a bore 500e for pivotal connection with the controlling rod.

40 Fig. 17 illustrates another embodiment of a

controlling member 521f, which in a similar manner may be substituted for the controlling member 521 formed by the controlling link 538 and the controlling arm 540 of the chair shown in Fig. 15.

According to the embodiment of Fig. 18 the back-rest 631 having the extension 634 is pivoted to the support 630 at 633 at a point spaced from the pivotal connection 694 between the rear end of the seat 632 and the support 630. A connecting link 635 pivoted at 636 to the extension 634 of the back-rest 631 is pivoted at 637 to the controlling link 638 swingably mounted on the support at 639. One end of a controlling rod 601 is pivoted at 600 to the controlling arm 640 rigidly connected with the controlling link 638. The other end of said controlling rod 601 is pivoted to the seat 632 at 602.

A leg-rest 664 swingably mounted on the seat 632 at 665 is pivoted to one end of a controlling bar 666 at 667. The other end of said controlling bar 666 is pivoted at 616 to an extension 617 of the controlling arm 640.

The sitting position of the movable members of the chair shown in full lines in Fig. 18 is limited by an abutment of the seat 632 against the upper edge of the support 630. The movable members of the chair may be held in any desired position by the locking device 643, which also includes limiting means as described above in connection with Figs. 2 and 3 for limiting the extreme reclined position of the movable members of the chair shown in dash and dot lines.

The controlling member 621 formed by the controlling link 638 and the controlling arm 640 with its extension 617 controls the movements of the seat 632 and the leg-rest 664 through the medium of the controlling rod 601 and the controlling bar 666 in dependence on the movements of the back-rest 631, which is connected with said controlling member through the medium of the connecting link 635.

Fig. 19 illustrates a different embodiment of a controlling member generally indicated by 621g, which may be substituted for the controlling member 621 formed by the controlling link 638 and the controlling arm 640 with its extension 617 of the chair shown in Fig. 18. Said controlling member 621g has a bore 639g for the swingable mounting of the controlling member on the support. Furthermore, said controlling member 621g has a bore 637g for pivotal connection with the connecting link, a bore 616g for pivotal connection with the controlling bar, and a bore 600g for pivotal connection with the controlling rod.

It is understood, that certain parts, elements, or mechanisms shown in a certain figure may be substituted for corresponding parts, elements, or mechanisms of the embodiments shown in other figures of the drawings.

I have described preferred embodiments of my invention, but it is understood that this disclosure is for the purpose of illustration, and that various omissions or changes in shape, proportion, and arrangement of parts, as well as the substitution of equivalent elements for those, herein shown and described, may be made without departing from the spirit and scope of the invention as set forth in the appended claims.

What I claim is:

1. A reclining article of furniture, comprising: a support, a back-rest pivotally mounted on said support, said back-rest having a downward extension, a seat, the rear portion of said

seat being swingably mounted on said support, a controlling member, said controlling member being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling member, said controlling member having a forward extension, and means positioned between the forward extension of said controlling member and said seat to effect movement of said seat in coordination with said controlling member.

2. A reclining article of furniture, comprising: a support, a back-rest pivotally mounted on said support, said back-rest having a downward extension, a seat, the rear portion of said seat being swingably mounted on said support, a controlling link, said controlling link being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling link, a controlling arm extending forwardly, the rear end portion of said controlling arm being fixedly connected with said controlling link, and means positioned between the front end of said controlling arm and said seat to effect movement of said seat in coordination with said controlling arm.

3. In a reclining article of furniture as claimed in claim 1, said means including a controlling rod, one end portion of said controlling rod being pivoted to said controlling member, the other end portion of said controlling rod being pivoted to said seat so as to effect movement of said seat in coordination with said controlling member.

4. In a reclining article of furniture as claimed in claim 1, said controlling member being in the shape of a plate.

5. In a reclining article of furniture as claimed in claim 2, said controlling link extending upwardly from its pivotal connection with said support, and said pivotal connection between the front portion of said connecting link and said controlling link being at the upper end of the latter.

6. In a reclining article of furniture as claimed in claim 2, said means including cooperating abutting surfaces arranged on the forward extension of said controlling arm and on said seat so as to effect movement of said seat in coordination with said controlling arm.

7. In a reclining article of furniture as claimed in claim 2, said controlling arm being of adjustable length, and means for setting a predetermined length of said controlling arm.

8. In a reclining article of furniture as claimed in claim 2, said controlling arm being of adjustable length, means for setting a predetermined length of said controlling arm, and cooperating abutting surfaces arranged on the forward extension of said controlling arm and on said seat so as to effect movement of said seat in coordination with said controlling arm.

9. A reclining article of furniture, comprising: a support, a back-rest pivotally mounted on said support, said back-rest having a downward extension, a seat, the rear portion of said

seat being swingably mounted on said support, a controlling member, said controlling member being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling member, said controlling member having a forward extension and being in the shape of a plate, and a controlling rod, one end portion of said controlling rod being pivoted to said plate-like controlling member, the other end portion of said controlling rod being pivoted to said seat so as to effect movement of said seat in coordination with said controlling member.

10. A reclining article of furniture, comprising: a support, a back-rest pivotally mounted on said support, said back-rest having a downward extension, a seat, the rear portion of said seat being swingably mounted on said support, a controlling member, said controlling member being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling member, said controlling member having a forward extension, and cooperating abutting surfaces arranged on said forward extension of the controlling member and on said seat so as to effect movement of said seat in coordination with said controlling member.

11. A reclining article of furniture, comprising: a support, a back-rest pivotally mounted on said support, said back-rest having a downward extension, a seat, the rear portion of said seat being swingably mounted on said support, a controlling member, said controlling member being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling member, said controlling member having a forward extension, and a roller mounted on said forward extension of the controlling member, said roller being in abutting engagement with said seat so as to effect movement of said seat in coordination with said controlling member.

12. A reclining article of furniture, comprising: a support, a back-rest pivotally mounted on said support, said back-rest having a downward extension, a seat, the rear portion of said seat being swingably mounted on said support, a controlling member, said controlling member being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling member, said

controlling member having an extension projecting forwardly and being spaced from the pivotal connections of said controlling member with said support and said connecting link, and means positioned between the forward extension of said controlling member and said seat to effect movement of said seat in coordination with said controlling member.

13. In a reclining article of furniture as claimed in claim 12, said means including a controlling rod, one end portion of said controlling rod being pivoted to said extension of the controlling member, the other end portion of said controlling rod being pivoted to said seat so as to effect movement of said seat in coordination with said controlling member.

14. In a reclining article of furniture as claimed in claim 12, said controlling member including said extension being in the shape of a plate.

15. In a reclining article of furniture as claimed in claim 12, said controlling member including said extension being in the shape of a plate, said means including a controlling rod, one end portion of said controlling rod being pivoted to said plate-like controlling member, the other end portion of said controlling rod being pivoted to said seat so as to effect movement of said seat in coordination with said controlling member.

16. A reclining article of furniture, comprising: a support, a back-rest pivotally mounted on said support, said back-rest having a downward extension, a seat, the rear portion of said seat being swingably mounted on said support, a controlling link, said controlling link being swingably mounted on said support at a point spaced from the pivotal connection between the back-rest and the support, a connecting link, said connecting link being pivoted at its rear end to said extension of the back-rest below the pivotal connection between the back-rest and the support and being pivoted at its front portion to said controlling link, a controlling arm extending forwardly, the rear end portion of said controlling arm being fixedly connected with said controlling link, and a controlling rod, one end of said controlling rod being pivoted to the front end portion of said controlling arm, and the other end of said controlling rod being pivoted to said seat.

ANTON LORENZ.
